Patented Dec. 15, 1914.

UNITED STATES PATENT OFFICE.

HARRY C. ADAM, OF ST. LOUIS, MISSOURI.

SEMI-INDIRECT-LIGHTING FIXTURE.

1,121,577.

Specification of Letters Patent. Patented Dec. 15, 1914.

Application filed February 25, 1914. Serial No. 821,030.

To all whom it may concern:

Be it known that I, HARRY C. ADAM, a citizen of the United States, residing at St. Louis, Missouri, have invented a certain new and useful Improvement in Semi-Indirect Lighting Fixtures, of which the following is a full, clear, and exact description, such as will enable others skilled in the art to which it appertains to make and use the same.

This invention relates to lighting fixtures of the type that produce a semi-indirect light.

In one form of semi-indirect lighting fixture that is now in use the top reflector is provided with a flat horizontally-disposed reflecting surface, and the shield or inverted bowl that is positioned under the lighting unit is formed from translucent material. The translucent shield or bowl reflects the secondary rays of light upwardly onto the top reflector, and these secondary rays are then projected downwardly through the translucent shield, and some of the direct rays that are reflected onto said top reflector are projected outwardly and downwardly without passing through the translucent shield. Owing to the fact that the reflecting surface on the top reflector is flat and is disposed in a horizontal plane, a large volume of the secondary rays which are projected downwardly through the translucent shield pass through the electric lamp bulb which constitutes the lighting unit, and if the bulb is old and blackened with age the rays fail to pass through same, thus causing a great loss of light. Furthermore, the rays that strike the top reflector at points outside the greatest diameter of the translucent shield, are projected downwardly at a very slight angle to a horizontal plane, and consequently are thrown radially or outwardly from the fixture in planes that are inclined downwardly only slightly with relation to the ceiling of the room. The upper edge of the inverted bowl or shield that is positioned under the lamp bulb, is lower than the top of the lamp filament, and consequently some of the direct rays pass over the upper edge of the shield without striking the top reflector, thus producing an intense glare on a horizontal plane which is very objectionable.

Still another objectionable feature of the lighting fixture above-mentioned is that it is not possible to form the top reflector of the same, when said reflector is of considerable

diameter, of porcelain enameled sheet metal owing to the tendency of the metal to twist and bend out of shape from the heat when it is being enameled, thus destroying the flat horizontally-disposed reflecting surface which is an essential feature of the top reflector.

The main object of my invention is to provide a semi-indirect lighting fixture of the general type above-mentioned but which is distinguished from the fixture of the particular form previously-described in that the top reflector is so designed that the direct rays will be thrown downwardly at a rather abrupt angle to a horizontal plane, and the secondary rays will be projected downwardly through the translucent shield without causing a large volume of the secondary rays to pass through the lamp bulb, thus causing the rays to be thrown where they are most needed and insuring an efficient light even after the lamp bulb has become blackened with age. To this end I have devised a semi-indirect lighting fixture in which the top reflector is provided with two independent reflecting surfaces that are disposed at a slight angle with relation to each other and also with relation to horizontal plane, one of said reflecting surfaces, namely the one that is located at the outer edge of the reflector causing the direct rays to be projected outwardly and downwardly at such an angle that the rays are concentrated instead of being thrown outwardly in a plane approximately parallel to the ceiling, and the other reflecting surface which is located at the center of the reflector causing a large volume of the secondary rays reflected from the translucent shield to be projected downwardly through said shield without striking or passing through the lamp bulb.

Another object is to provide a semi-indirect lighting fixture which is so designed that none of the direct rays from the light can escape without striking the translucent shield or the top reflector, thus eliminating an intense horizontal glare.

Another object is to provide a semi-indirect lighting fixture having a top reflector of the character above described which comprises a portion that surrounds the skirt of the electric lamp bulb and thus serves as a reflector for the secondary rays that are concentrated at the center of the top reflector.

Another object is to provide a collapsible means of novel construction for holding the inverted bowl or translucent shield of the fixture, which means is so designed that 5 standard glassware may be used to form the diffusing shield of the fixture. And still another object is to provide a semi-indirect lighting fixture in which the means that sustains the top reflector and holds it in position 10 also carries the lamp socket, and is so designed that the electric wires that supply current to the lamp can lead into the side of the lamp socket and thus comply with certain requirements of the fire-underwriters.

15 Other objects and desirable features of my invention will be hereinafter pointed out.

Figure 1 of the drawings is a vertical sectional view of an indirect lighting fixture constructed in accordance with my invention; and Fig. 2 is a perspective view of the positioning block that forms part of the means for supporting the inverted bowl or diffusing shield of the fixture.

Referring to the drawings which illustrate the preferred form of my invention, A designates the top reflector of the fixture which is round, and B designates the diffusing shield that is positioned under the lighting unit which preferably consists of 25 an electric light bulb C, said shield being in the form of an inverted bowl. The top reflector A can be formed from any suitable material, and it can either be provided with a plain edge or a flanged edge, the reflector 30 A herein shown being provided at its outer edge with a vertically-disposed flange 1 whose upper edge bears against the ceiling, as shown in Fig. 1. Adjacent the outer edge of the top reflector A is a reflecting surface 2 which is inclined upwardly from the outer edge of the reflector, and adjacent the center of the reflector is an oppositely inclined reflecting surface y, said reflecting 35 surfaces either merging into each other or 40 else merging into a flat or horizontally disposed ring-shaped portion z, as herein shown.

While I have herein illustrated my invention embodied in a semi-indirect lighting fixture that is provided with a round top reflector and a substantially inverted semi-spherical-shaped diffusing shield. I wish it to be understood that my invention is not limited to a fixture provided with a top reflector and a diffusing shield of the exact form herein illustrated, for the top reflector and diffusing shield could be of various other forms without departing from the spirit of my invention.

60 The upper edge of the diffusing shield or translucent bowl B preferably terminates at a point above the filament f of the electric light bulb C so as to prevent any rays from escaping over the upper edge of said shield 65 without striking against the top reflector A.

In view of the fact that the reflecting surface x inclines upwardly from a horizontal plane the direct rays x' that strike against same will be projected downwardly and also outwardly in approximately the planes indicated by the broken lines x^2 in Fig. 1, thus causing the light to be concentrated instead of being thrown across the room in planes approximately parallel to the ceiling of the room. The secondary rays y' that strike against the upper edge portion of the shield B, are reflected onto the reflecting surface y of the top reflector A and are thence projected downwardly in substantially straight lines, as indicated by the broken lines y^2 , without striking or passing through the lamp bulb C. Consequently there is very little loss of light with my improved fixture when the lamp bulb becomes blackened with age, owing to the fact that the top reflector is provided with a reflecting surface which is so disposed that a large volume of the secondary rays which are reflected onto same from the diffusing shield, will be projected downwardly through said shield without passing through the lamp bulb. Moreover, there is no horizontal glare between the top reflector and the diffusing shield for said shield is so proportioned and is so positioned with relation to the top reflector that none of the direct rays can escape without passing through the shield or striking against the top reflector.

I prefer to provide the top reflector A with a reflecting portion 2 that surrounds the metal skirt 3 of the electric lamp and thus serves as a reflector for the secondary rays that concentrate at the center of the top reflector.

It is immaterial so far as my broad idea is concerned how the top reflector is sustained in position or how the translucent bowl or diffusing shield B is supported, but I prefer to provide the fixture with a supporting member D for the top reflector which may be formed from cast metal or drawn sheet metal and which is substantially inverted cup-shape so that it will serve as a housing for the porcelain receptacle 4 in which the lamp socket 5 is mounted, said porcelain receptacle 4 being secured by means of screws 6 or other suitable devices to the top wall of the member D or to a ring-shaped device 7 that is secured to said top wall. At the upper end of the member D are wings or lugs 8 through which screws 9 or other suitable fastening devices pass so as to secure the member D to an outlet box or other suitable support 10 in the ceiling. At the lower end of the member D are wings or lugs 11 to which the top reflector A is connected by means of screws 12 or other suitable fastening devices. In the side of the members D are openings 13 for the wires 14 which supply electric current to the lamp 130

C, thus permitting the wires to be led in through the side of the member D and connected to the lamp socket without passing through the top of said member, a requirement which is some times insisted upon by the fire-underwriters. In practice I prefer to provide the member D with side openings 13 for the wires and also form a knock-out portion 15 in the top wall of the member D, for a purpose well understood by those familiar with this art.

One feature of my improved fixture which I believe is novel is the collapsible supporting or sustaining means that I prefer to use for holding the shield B in position, said means being so designed that it can be packed conveniently for shipping and also permits the use of standard glassware to form the diffusing shield of the fixture. By standard glassware I mean glass shades or reflectors such as are now in general use on direct electric lighting fixtures, and which are provided at the top with an opening so as to permit the electric light bulb to be screwed into the socket from which the shade is suspended.

By referring to Fig. 1 of the drawings it will be seen that the means that I prefer to use for supporting the shield of my improved fixture consists of a plurality of arms 16 arranged inside of the shield B and connected at their lower ends to a member 17 that fits inside of an opening formed in the bottom of the shield B, said member operating with a cap-piece 18 to form a closure for the opening in the shield. The upper ends of the arms 16 are provided with hooks 16^a that project through the links of chains 19 suspended from hooks 20 which preferably pass through the ring-shaped portion z of the top reflector and are securely connected thereto by nuts or in any other suitable manner. The member 17 and cap-piece 18, which form a closure for the opening in the bottom of the shield B, are clamped to the shield by means of a bolt 21 which passes through a washer 22 and through a positioning block 23, between which hook-shaped extensions at the lower ends of the arms 16 are clamped, said block 23 having grooves 23^a formed in the upper edge of same for receiving the arms 16 so as to hold said arms in a certain position with relation to each other. The positioning block 23 rests upon the member 17 and, consequently when the nut 21^a on the bolt 21 is tightened the arms 16 will be securely clamped between the washer 22 and the positioning block 23 and the member 17 and cap-piece 18 will be securely clamped to the shield B when the ornamental nut 21^b on the extreme lower end of the bolt is tightened.

A fixture of the construction above-described can be manufactured at a low cost,

owing to the fact that standard glassware can be used to form the diffusing shield of the fixture; it can be packed conveniently for shipping, owing to the fact that the means which sustains the inverted shield or bowl in position is collapsible and can be shipped in knock-down form; and furthermore, is so designed that it is not necessary to form perforations or holes in the diffusing shield in order to secure it to its sustaining means. And still another desirable feature of said fixture which is very important from a manufacturing standpoint is that the top reflector can be formed in large sizes from porcelain enameled steel, owing to the fact that the angularly-disposed portions of said top reflector impart sufficient stiffness to same to prevent it from buckling or bending out of shape during the operation of enameling the reflector. These, in addition to the desirable features previously-mentioned in regard to the reflection of the light, make my fixture a decided improvement upon semi-indirect electric lighting fixtures heretofore in use.

Having thus described my invention, what I claim as new and desire to secure by Letters Patent is:

1. A semi-indirect lighting fixture, comprising a top reflector and a translucent diffusing shield arranged above and below the lighting unit, respectively, the upper edge portion of said shield being flared outwardly and said top reflector having a reflecting surface, straight or uncurved in transverse cross section from its inner to its outer edge, that projects outwardly and upwardly away from the lighting unit and which is disposed at such an angle that indirect rays of light which are reflected onto same from the flared upper portion of the translucent diffusing shield will be projected downwardly in substantially vertical paths without passing through the lighting unit.

2. A semi-indirect lighting fixture comprising a top reflector and a translucent diffusing shield arranged above and below the lighting unit, respectively, said shield having an outwardly flared upper edge portion and said top reflector being provided with two oppositely inclined reflecting surfaces arranged in concentric relation, the inner reflecting surface being in the form of an inverted frustum of a cone onto which indirect rays are projected from the outwardly flared portion of said diffusing shield.

3. A semi-indirect lighting fixture comprising a top reflector and a translucent diffusing shield arranged above and below the lighting unit, respectively, the upper edge portion of said shield being inclined or flared outwardly and said top reflector being provided with angularly-disposed re-

flecting surfaces that are inclined in opposite directions to each other, one of said inclined reflecting surfaces acting to project the rays downwardly which are reflected onto same from the flared portion of said shield.

4. A semi-indirect lighting fixture comprising a top reflector and a translucent diffusing shield arranged above and below the lighting unit, respectively, said shield being provided adjacent its upper edge with a portion that inclines outwardly away from the lighting unit and said top reflector being provided adjacent its outer edge with a reflecting surface which inclines upwardly toward the center of the reflector, and adjacent its center with an independent reflecting surface consisting of an oppositely inclined surface onto which indirect rays are reflected from the inclined portion of said shield.

5. A semi-indirect lighting fixture comprising a top reflector and a translucent diffusing shield arranged above and below the lighting unit, respectively, said shield having a portion that inclines outwardly away from the lighting unit and said top reflector being provided with two reflecting surfaces that form practically the entire underside of the reflector, the inner one consisting of an inclined reflecting surface disposed at such an angle that the major portion of the reflected secondary rays from the inclined portion on the shield are projected downwardly in paths outside of the lighting unit, and the outer one consisting of an oppositely inclined surface disposed at such an angle that the direct rays are projected downwardly at rather abrupt angles to a horizontal plane.

6. In a semi-indirect lighting fixture, a top reflector, a substantially bowl-shaped translucent diffusing shield whose upper edge portion flares outwardly, and a lighting unit arranged intermediate said reflector and shield, said top reflector consisting of a member having a center opening through which the lighting unit or the supporting means for same passes, and provided on its underside with two reflecting surfaces, the outer one of which inclines upwardly from the outer edge of said member and the inner one of which inclines upwardly from the center opening in said member so that it will project the rays downwardly which are reflected onto same from the outwardly flared portion at the upper edge of said shield.

7. In a semi-indirect lighting fixture, a top reflector, a substantially bowl-shaped translucent diffusing shield, and a lighting unit arranged intermediate said reflector and shield, said top reflector consisting of a member having a center opening through which the lighting unit or the supporting

means for same passes, and provided on its underside with two reflecting surfaces, the outer one of which inclines upwardly from the outer edge of said member and the inner one of which inclines upwardly from the center opening in said member so that it will project the rays downwardly which are reflected onto same from said shield, said reflecting surfaces merging into a horizontally disposed integral portion of said member.

8. A top reflector for a semi-indirect electric lighting fixture provided with two oppositely inclined reflecting surfaces and also with a reflecting portion that covers the skirt of the electric light bulb which constitutes the lighting unit, one of said reflecting surfaces inclining upwardly from the outer edge of the reflector and the other reflecting surface inclining upwardly from the reflecting portion that covers the skirt of the lamp bulb.

9. A semi-indirect electric lighting fixture comprising a top reflector and a translucent diffusing shield arranged above and below the electric light bulb, respectively, and consisting of separate and distinct members that are spaced away from each other, said diffusing shield having an outwardly flared portion that extends above the upper end of the filament of the bulb and the top reflector being provided adjacent its center with an inverted frusto-conical-shaped reflecting surface onto which indirect rays are reflected from the flared upper edge portion of the diffusing shield and provided at its outer edge portion with an oppositely inclined reflecting surface of frusto-conical-shape form.

10. In a semi-indirect lighting fixture, a shield that is adapted to be arranged under the lighting unit and which is provided at its lower end with an opening, coöperating members detachably connected together so as to form a closure for said opening, and a collapsible sustaining means for the shield detachably connected to said closure members.

11. In a semi-indirect lighting fixture, a shield that is adapted to be arranged under the lighting unit and which is provided at its lower end with an opening, a member that fits in said opening, sustaining arms arranged inside of the shield, a positioning device supported by said closure member for holding said arms in position, and means for clamping said arms to said positioning device.

12. In a semi-indirect lighting fixture, a shield that is adapted to be arranged under the lighting unit and which is provided at its lower end with an opening, coöperating members arranged on opposite sides of the shield and forming a closure for said opening, sustaining arms arranged inside of the

shield, a positioning device that engages said arms and holds them in a certain position with relation to each other, and means for clamping said arms to said positioning device and for clamping said closure members to the shield.

13. In a semi-indirect lighting fixture, a top reflector, a shield that is adapted to be arranged under the lighting unit, a plurality of arms arranged inside of said shield and sustained from said top reflector, and means for securing the lower ends of said arms to the bottom portion of said shield.

14. In a semi-indirect lighting fixture, a top reflector, and a sustaining member for said top reflector provided with an electric lamp socket and having a side opening through which the wires can be led to the side of the lamp socket.

15. In a semi-indirect lighting fixture, a top reflector, a sustaining member arranged above said reflector and provided with portions to which said reflector can be connected, an insulator arranged inside of said sustaining member and provided with an electric lamp socket, and means whereby the electric wires can be led in through the side of said sustaining member.

16. In a semi-indirect electric lighting fixture, a top reflector, an inverted cup-shaped sustaining member for said reflector which is arranged above same and which is provided adjacent its upper end with means for securing it to an outlet box or other suitable support, an insulator arranged inside of said member for receiving an electric lamp socket, and openings in the side of said sustaining member for the wires that are connected to said socket.

17. A semi-indirect lighting fixture comprising a top reflector provided adjacent its center with reflecting surface that inclines upwardly from the lighting unit and provided adjacent its outer edge with an oppositely inclined reflecting surface, and a diffusing shield arranged under the lighting unit and having its upper edge spaced away from the underside of said top reflector so that some of the rays can pass over the upper edge of the shield and strike the inclined reflecting surface at the outer edge of the top reflector, said shield being of less diameter than said top reflector and having its upper portion flared outwardly.

18. A semi-indirect lighting fixture comprising a one-piece top reflector provided at its center with an opening for the lighting unit, said reflector having two oppositely inclined reflecting surfaces, the inner one of which inclines upwardly and outwardly away from the lighting unit and the outer one of which inclines upwardly and inwardly toward the lighting unit, and a diffusing shield of less diameter than said top reflector arranged under the lighting unit and provided with side walls whose upper portions flare outwardly so that the indirect rays which strike same will be projected onto the inclined reflecting surface adjacent the center of the top reflector.

In testimony whereof I hereunto affix my signature in the presence of two witnesses, this twentieth day of February 1914.
